[57] CLAIM

The ornamental design for a personal optical care container, as shown and described.

DESCRIPTION

FIG. 1 is a perspective view of a personal optical care container showing my new design in an open condition; FIG. 2 is a left side elevational view thereof, the lid shown returned to a closed position; FIG. 3 is a right side elevational view of FIG. 1; FIG. 4 is a top plan view of the lid component shown in FIG. 1; FIG. 5 is a bottom plan view of FIG. 4; FIG. 6 is a top plan view of the Container portion of shown in FIG. 1, the broken lines showing the container contents being included for illustrative purposes and forming no part of the claimed design; FIG. 7 is a bottom plan view of FIG. 6; FIG. 8 is a front elevational view of FIG. 2; FIG. 9 is a rear view of FIG. 8; and, FIG. 10 is a rear view of FIG. 2, the handle shown separated to reveal a carrying chord.
